UNITED STATES PATENT OFFICE.

ROBERT STRAFFORD-COLLINS, OF ELMHURST, NEW YORK.

FOLDABLE RECEPTACLE-FORM.

1,293,716.

Specification of Letters Patent. Patented Feb. 11, 1919.

Application filed January 26, 1918. Serial No. 213,989.

To all whom it may concern:

Be it known that I, ROBERT STRAFFORD-COLLINS, a citizen of Canada, residing in the city of Elmhurst, county of Queens, and 5 State of New York, have invented certain new and useful Improvements in Foldable Receptacle-Forms, of which the following is a full, clear, and exact specification.

My invention relates to a form capable 10 of being folded into a receptacle and refers particularly to a form foldable into a cross-shaped receptacle.

The device of my invention may be composed of paper, card-board, metal or other 15 material suitable for the production of receptacles and is of the general form and construction as shown in the accompanying drawings, in which similar parts are designated by similar numerals.

20 Figure 1 is a plan view of my device.

Fig. 2 is a top plan view of my device partially folded.

Fig. 3 is a top plan view of my device in folded form.

25 Fig. 4 is a side plan view in the direction of arrow 4 of Fig. 3.

The form of my invention, as illustrated in the accompanying drawings, comprises a member 1—2—3—4—5. Integral with the 30 member 1 are the members 6 and 7, the former carrying the tongue 8 and the latter having the opening 9. Integral with the one arm of the member 2 is the member 10, integral with which are the members 11 and 12, the 35 former having the opening 13 and the latter carrying the tongue 14. Integral with the opposite arm of the member 2 is the member 15, integral with which are the members 16 and 17, the former carrying the tongue 18 40 and the latter having the opening 19. Integral with the member 2 are the members 20, 21, 22, 23, 24, 25, 26 and 27. Integral with the member 3 are the members 28 and 29, the former having the opening 30 and 45 the latter carrying the tongue 31. Integral with the member 4 are the members 33 and 34 and also the members 35, 36, 37, 38, 39, 40, 41 and 42. As the device indicated is for a bank, a cross-shaped opening 43 is 50 made in the member 4. The dotted lines indicate scorings to facilitate the ease of folding the device and may be incorporated upon the device, if desired. The various tongues are of such a size and shape as to be insertible through the various openings and 55 to lock together the respective members.

One method of folding the device is as follows:—

Members 3, 4 and 5 are folded at a right angle along the line A—B, member 10 is folded along the line C—D, member 1 is folded along the line E—F and member 15 is folded along the line G—H. The members 28, 12, 11, 6, 7, 16 and 17 are then folded inwardly at right angles to form 65 the indented sides and the tongues 14, 8, 18 and 31 inserted through the adjacent openings 30, 13, 9 and 19. If the member 4 be then bent outwardly along the line K—L, the device will have the form shown 70 in Fig. 2. If now the members 20, 21, 22, 23, 24, 25, 26 and 27 be folded upwardly along their scored lines, the member 4 be folded along the line K—L over the top of the device and the members 35, 36, 37, 38, 75 39, 40, 41, 42, 33, 34 and 5 be folded downwardly along their scored lines, the device will have the form shown in top plan view of Fig. 3 and side plan view of Fig. 4. The various triangular shaped members and 80 members 33, 34 and 5 may be pasted to the sides upon which they abut, thus forming a rigid box of the shape indicated.

From the above it is shown that the member 1—2—3—4—10—15—3 forms the top, 85 bottom and extended sides of the receptacle, the members 12, 11, 6, 7, 16, 17, 29 and 28 form the indented sides of the receptacle, the corner members 20, 21, 22, 23, 24, 25, 26, 27, 35, 36, 37, 38, 39, 40, 41 and 42 are 90 each folded against an indented side, the members 33, 34 and 5 are each foldable against an extended side, the member 2 forms the bottom of the receptacle, the member 4 forms the top of the receptacle and the members 10, 1, 15 and 3 form the extended 95 sides.

As the side members 1, 15, 3 and 10 with their integral members, are two-thirds the width of the width of the bottom member 2, the box will be two-thirds as high as it is wide at the top and bottom. It is evident that these members may be varied to give any desired comparative dimension between the height and width. 100

As the four arms of the bottom member 2 and the top member 4 are equal, a top plan view will show a cross of equal arms, and it is evident that the various members may be so varied as to form a cross with 105 unequal arms, if desired.

It is further evident that each of the 110

members may be produced separately and then properly connected together by a hinging material to allow of the device being folded and my invention and claims cover 5 a construction of this character.

I do not limit myself to the particular size, shape, number or arrangement of parts as described and shown all of which may be varied without going beyond the scope 10 of my invention as described and claimed.

What I claim is:—

1. A blank comprising a sheet of material capable of being folded to form a four-armed cross-shaped receptacle in which the 15 top and bottom are parallel to each other, the ends of the opposite arms are parallel to each other and the opposite sides of each

arm are parallel to each other and means carried by the blank for maintaining the sheet in its folded position. 20

2. A blank comprising a sheet of material having extended tongues and openings capable of receiving said tongues, capable of being folded to form a four-armed cross-shaped receptacle in which the top and bottom are parallel to each other, the ends of the opposite arms are parallel to each other and the opposite sides of each arm are parallel to each other. 25

Signed at New York, in the county of 30 New York and State of New York this 24 day of January, 1918.

ROBERT STRAFFORD-COLLINS.
